RADIO POWER PACK

Filed May 25, 1927

UNITED STATES PATENT OFFICE.

ISIDOR KITSÉE, OF PHILADELPHIA, PENNSYLVANIA.

RADIO POWER PACK.

Application filed May 25, 1927. Serial No. 194,117.

My invention relates to an improvement in radio power packs. I will describe here my invention as applied to "A" eliminators, it being understood that substantially the same circuit may be used for "B" and "C" eliminators, but it is obvious that transformers of different values have to be employed. In the accompanying drawing, which illustrates one form my invention may take, 10 and 2 are the circuit wires supposedly carrying an alternating current; 3 is the primary of a transformer; 4 and 5 the two secondaries thereof. The secondary 4 comprises here the two parts 6 and 7; 8 is the midtap 15 of the secondary 4; 9 and 10 are the terminal wires of said secondary; 11 and 12 are the terminal wires of the secondary 5; 13 is a choke coil connected with one terminal to the midtap 8 of the secondary 4 and with the 20 other terminal to the conductor 14 adapted to be connected to the A minus terminal of the radio circuit. 15 is a housing with the atmospheric gases removed and preferably filled with an inert gas such as argon. 16 is 25 the stem adapted to seal the housing, this stem carries the necessary conductors, hereafter to be enumerated.

To the terminal conductors 11 and 12 of the secondary 5 are connected the conductors 30 17 and 18 going through the stem 16 into the housing 15. To these conductors 17 and 18 are connected the filaments 19 and 20 in multiple arc. The terminal 9 of the secondary 4 connects through the stem 21 with the complementary plate 22. The terminal 10 35 of the secondary 4 connects through stem 23 with the complementary plate 24. To the lower terminal of the choke 13 is connected the conductor 25 in contact with stem 26 and 40 to this stem is connected the filament 27. To the jointure of 12 and 18, outside the housing, is connected the conductor 28; the choke coil 30 is connected with one terminal through 29 with 28 and with the other terminal to 31 adapted to be connected to A 45 plus terminal of the radio set. In shunt to 14 and 28 is connected the resistance 32, the connection being indicated by dotted lines, as this shunt is only required in extreme 50 cases.

The secondary 4 supplies the required energy to actuate the thermionic valves of a radio set and the two filaments 19 and 20 with their complementary plates 22 and 24 55 act as the full wave rectifiers to convert the A. C. into D. C. The filament 27 acts as the

filter for the rectified current to smooth out the so-called ripples or inequalities of said rectified current.

To eliminate all interference or so-called "hum" I make use of the second choke coil, here designated by the numeral 13. In the employment of the two choke coils 13 and 30 I have found in actual practice that it is of great advantage to make the choke coils of 60 different resistances and therefore different henries and for this reason all the sets made in accordance with this my invention have the coil 13 of a gauge lower than the coil 30 or of a different number of convolutions, but 65 in practice the different gauged wire suffices.

I have also found in practice that a small condenser, .25 microfarads capacity over-bridging the outer terminals 9 and 10 of the secondary 4 is of some advantage with practical operation of the device and this small condenser may be connected to the points here indicated by X and Y. 75

It should be noted that aside from this small condenser, which in reality is not an absolute necessity, no condensers or large resistances are employed in my system. The value of the little resistance 32 should not exceed 20 ohms and its carrying capacity should be far less than $\frac{1}{2}$ ampere. In reality the small condenser and little resistance are only refinements and may be omitted without interfering with the operation of the device. 85

From the description and illustration of 90 this system and its circuit the great advantage over existing systems and circuits lies not only in the elimination of condensers and resistances but also in the elimination of so-called filter cells, electrolytic or otherwise, 95 and the employment of one housing embodying the entire rectifying and filtering means as well as the different values of the choke coils when employed and in fact of the whole arrangement and connections of the different parts of the circuit. 100

It may not be amiss to state that a number of instruments made in accordance with this my invention are successfully operating different types of radio sets and are entirely free from the so-called "hum" or similar interference. 105

Having now described my invention what I claim as new and desire to secure by Letters Patent is:

1. In a radio power pack a transformer having a main secondary and cathode

heater secondary, a circuit connecting with one terminal to the center-tap of the secondary and with another terminal to one terminal of the cathode heater secondary, 5 said circuit embracing a filament adapted to be heated through the passage of part of the current flowing from the center tap to one terminal of the cathode heater, said filament acting as one of the filters of said power pack.

2. In a radio power pack a power secondary, a center-tap for said secondary, a cathode heater secondary, a rectifying tube for full wave rectification, an auxiliary filament in said tube, said auxiliary filament connected with one terminal to the center-tap of the power secondary and with the other terminal to one conductor of the cathode heater secondary.

15 3. In a radio power pack, a transformer having secondary windings, a full wave rec-

25 tifying tube, the anodes and cathodes thereof connected to their proper secondaries, a filter circuit for said power pack, said filter circuit comprising an auxiliary filament positioned in said rectifying tube and connected with one terminal to one side of the cathode secondary and with the other terminal to the center-tap of the anode secondary, and including a non-inductive resistance between said center-tap and said filament.

30 4. In the art of filtering a rectified current useful for radio work, the improvement which consists in causing said rectified current to pass in part through a filament positioned in an evacuated envelope and in part through comparatively small non-inductive resistance and choke coils.

35 In testimony whereof I affix my signature.

ISIDOR KITSÉE.
